UNITED STATES PATENT OFFICE.

GEORGE LANCE BROWN, OF HUNTINGDON VALLEY, PENNSYLVANIA.

ART OF HANDLING CAPSULES FOR FILLING.

Application filed April 17, 1926. Serial No. 102,613.

This invention relates to capsule filling and it has for its principal object the simple, effective, cleanly, economical and expeditious filling of capsules with medicine.

5 Other objects and advantages of my invention will be set forth hereinafter as they will be more readily understood in connection with the description of the invention.

How the foregoing together with such 10 other objects and advantages as may herein-after appear or are incident to my invention, are realized, is illustrated in preferred form in the accompanying drawings wherein—

Fig. 1 is a front elevational view of the device showing a portion of a capsule ejecting 15 mechanism in broken section;

Fig. 2 is an enlarged fragmentary sectional elevation thru the table, the movable head and certain of the frame parts with 20 some of the parts appearing in full view;

Fig. 3 is a cross section taken on the line 3—3 of Fig. 2;

Fig. 4 is a plan section taken on the line 4—4 of Fig. 3; and

25 Figs. 5 to 8 inclusive are reduced fragmentary, diagrammatic views showing various operative positions of certain parts of the device.

Referring to the drawings it will be seen 30 that the device in general comprises a frame or supporting structure A; a table B supported on the frame A by means of the brackets 9; a movable head C adapted to be moved up and down on the guides 10, which 35 guides are secured to the frame A at their lower ends and braced at their upper ends by the member 11; and a mechanism D for imparting movement to the head C, which mechanism is here shown as comprising a 40 forked lever 12 pivoted at 13 to the link 14.

The movable head C is provided with an upwardly extending rod 15 which passes thru an opening in the stop member 16.

This stop member 16 is engaged by the 45 flanged member 17 of the head C as it is moved upwardly thus limiting the movement of the head in this direction, and at the same time serving to give rigidity to the extending portion of the head.

50 Referring now to the construction of the table B it will be seen that it comprises a plate-like member 18 having a plurality of holes or apertures 19 of a diameter to accommodate the body portion 20 of the capsules 21, the thickness of the plate at that portion where the holes are located being

in this instance somewhat greater than the length of a capsule body. The member 18 is provided with an annular portion 22 to which is secured the plates 23 and 24 whereby a chamber 25 is provided in the table B for the purpose to be hereinafter described. Suitable ears are provided on this table having apertures thru which the guides 10 pass, whereby the head C is aligned with the table B, similar ears thru which the guides 10 pass of course being provided on the head C. Within the chamber 25 a pin carrying member 26 is located having a shank 27 extending thru the plate 23, a shouldered portion 70 being provided on the shank 27 for limiting the downward movement of the member 26 influenced by the springs 28. It is to be noted that the member 26 has secured thereto a plurality of pins 29, one for each capsule receiving aperture 19 and that these pins are spaced on centers corresponding to the centers of the apertures 18, the diameter of the pins being smaller than the diameter of the apertures so that an annular space is provided between the pins and the apertures. The member 26 with its pins 29 constitutes 75 in effect a movable bottom for the apertures 18 and it is to be observed that the length of the pins, and the location of the shank shoulder, is such as will cause the pins to project somewhat into the apertures when in the position shown in Fig. 2. Therefore when a capsule body is in place in its aperture the open edge thereof is flush with the 80 table top, as clearly indicated in Figs. 2, 3 and 6.

The construction of the head C is very similar to that of the table it being pointed out however that the apertures 30 therein 95 are of a diameter to accommodate the caps 31 of the capsules 21 and that the pins 32 are correspondingly of larger diameter. The pin carrying member 32 located within the chamber 33 in this case constitutes in 100 effect a movable top for the apertures and is normally held against the stops 34 under the influence of the spring 35.

The upwardly extending rod 15 hereinbefore mentioned, in this instance is hollow 105 and has extending therethrough the rod 36, reduced in diameter at 37 (see Fig. 2), and secured at this end to the member 32. The upper end of the rod 36 extends beyond the hollow rod 15 and its associated parts and 110 is provided with a knob 38 whereby it may be operated to move the pin carrying mem-

ber 32 as will further appear. Similarly the pin carrying member 26 may be moved by means of the lever 39.

The chamber 25 of the table B and the chamber 33 of the head C are connected to any suitable form of vacuum creating device in this instance being shown as a vacuum tank 41 connected to the vacuum pump 40. The vacuum tank 41 is provided with a pipe 42 having the branches 43 and 44 each provided with a manually operable valve 45 and 46 respectively. A conduit 47 is led from the valve 45 to the pipe 48 which communicates with the chamber 25 of the table B and a conduit 49 is led from the valve 46 to the T 50 of the hollow rod 15 which hollow rod communicates with the chamber 33 of the head C. Thus by operating the valves a vacuum may be created or destroyed in the chambers for purposes now appearing.

In the manufacture of capsule shells it is the usual procedure to assemble the capsules for delivery to the trade; therefore, in order to fill them with medicine it is necessary to disassemble, fill and reassemble them; and how this is accomplished by the employment of my device will now be described.

An empty assembled capsule is inserted in each of the plurality of apertures 19 in the table or support B with the body portion 20 thereof down, as clearly shown in Fig. 5 it being observed that the caps 31 rest on the table top. Next the head C is moved downwardly on the guides 10 until it abuts or substantially abuts the table B by means of the mechanism D whereupon the valves 45 and 46 are opened creating a suction in the apertures 19 and 30 which causes the caps to become separated from the bodies, the caps being brought into abutment with the pins 32^a of the member 32 which is in its normal position, and the bodies being brought into abutment with the pins 29 of the member 26 which is also in its normal position. The head C is then raised and the caps are carried therewith under influence of the suction. Fig. 6 clearly shows this position of the parts, the capsule bodies however having been filled with medicine in any suitable manner. One method of filling the bodies would be to place a quantity of medicine, somewhat more than what is known to be the capacity of the plurality of capsules, on the table and to spread it over the surface until all of the bodies are filled and then to remove all surplus from the table top which surplus might be allowed to remain on the shelf E surrounding the table for subsequent use.

The next operation is to again bring the head C down, in this case bringing it in direct contact with the table B. The valve 45 may then be closed and the lever 39 operated to move the pin carrying plate 26 up-

wardly whereby the capsule bodies are moved into the caps, as shown in Fig. 7.

Having thus filled and reassembled the capsules the next step is to eject them from the mechanism which I accomplish by again raising the head C with the suction still on so that the filled, assembled capsules are carried therewith as shown in Fig. 8. The valve 46 may then be closed and the knob 38 depressed which moves the pin carrying member 32 downwardly causing the pins 32^a to eject the filled capsules and completing the operations.

It is to be understood that the capsules may be ejected in various other ways as for example by means of air pressure as shown in Fig. 1, the air being admitted to the cylinder 51 by means of the valve controlled inlet pipe 52 and acting on the piston portion 53 of the rod 36. Another method would be to connect the inlet pipe 52 directly to the chamber 33 and by opening the valves the capsules would be blown out.

In some instances it might be desirable to release the suction from the caps in the last operation above mentioned so that the capsules would remain in the table from which they could be ejected in any suitable manner.

I claim:

1. A capsule filling device comprising in combination, a holder for a plurality of empty assembled capsules, suction means for separating the parts of the capsules, means for reassembling the capsules after they have been filled, and means for ejecting the filled capsules.

2. A capsule filling device comprising in combination, a holder for a plurality of capsule bodies, a holder for a plurality of capsule caps, suction means associated with said holders for preventing displacement of the bodies and caps from their respective holders, said holders being adapted to be brought together so that the bodies and caps are brought into alignment and means operable to assemble the bodies and caps after filling.

3. A capsule filling device comprising in combination, a holder for a plurality of capsule bodies, a holder for a plurality of capsule caps, suction means associated with said holders for preventing displacement of the bodies and caps from their respective holders, said holders being adapted to be brought together so that the bodies and caps are brought into alignment and means operable to assemble the bodies and caps after filling together with means for ejecting the filled assembled capsules.

4. A capsule filling device comprising in combination a holder for a plurality of empty capsules, a holder thereabove, said holders being adapted to be brought together, suction means associated with each

of said holders operating to hold one part of the capsules in one holder and the other part in the other holder when said holders are separated, and means for capping said 5 capsules when the holders are brought together.

5. A capsule filling device comprising a fixed support for a plurality of capsules, a carrier movable to and away from said support, means adapted to hold the capsules to the support, suction means operating when the carrier is brought to the support to hold one part of the capsules to the carrier whereby said part is separated from the 10 remaining part held in the support, said support and carrier when separated giving accessibility to the capsules for filling, and means for capping the capsules when the carrier is again brought to the support.

20 6. A capsule filling device comprising a pair of suction heads each having a plurality of capsule receiving apertures, means for aligning the apertures in one head with the apertures in the other head, suction means for holding one part of the capsules in the apertures of one head and the other 25 part in the apertures of the other head said suction means being valve controlled whereby said means may be operated either to hold one part of the capsules to one head and the other part to the other head or to hold assembled capsules to either head, for 30 subsequent ejection.

7. A capsule filling device comprising a 35 pair of suction heads each having a plurality of capsule receiving apertures, means for aligning the apertures in one head with the apertures in the other head, suction means for holding one part of the capsules in the apertures of one head and the other part in 40 the apertures of the other head said suction means being valve controlled whereby said means may be operated either to hold one part of the capsules to one head and the

other part to the other head or to hold 45 assembled capsules to either head together with means for ejecting the capsules so held.

8. A capsule filling machine comprising in combination a plate having a plurality of apertures for receiving empty assembled 50 capsules; a second plate having a plurality of apertures, said second plate being mounted with respect to said first plate so that its apertures align with the apertures of the first plate; a movable member associated with each of said plates having a plurality of pins of less diameter than the diameter of the aforesaid apertures, constituting movable bottoms for said apertures; and means for creating a suction in the aforesaid apertures whereby the parts of the capsule may be separated.

9. A capsule filling machine comprising in combination a holder for a plurality of capsule shells, a second holder for the caps 65 of said shells, said holders being adapted to be brought together, means associated with each of said holders whereby the parts of the shell may be separated, means associated with one of said holders for assembling the 70 shell after one part thereof has been filled, and means for ejecting the filled assembled capsules.

10. A capsule filling device comprising a pair of suction heads each having a plurality of capsule receiving apertures, said heads being so mounted that the apertures in one align with the apertures in the other, suction means for holding one part of the capsules in the apertures of one head and the other 80 part in the apertures of the other head, means associated with one head for assembling the capsules after filling, and means associated with the other head for ejecting the assembled capsules.

In testimony whereof, I have hereunto signed my name.

G. LANCE BROWN.
